UNITED STATES PATENT OFFICE.

JOHN S. COLDWELL, OF MILWAUKEE, WISCONSIN, ASSIGNOR TO THE CUTLER-HAMMER MFG. CO., OF MILWAUKEE, WISCONSIN, A CORPORATION OF WISCONSIN.

WEB-SUPPLYING SYSTEM.

Application filed December 6, 1924. Serial No. 754,241.

This invention relates to web supplying systems for printing presses and other receiving machines.

The invention has among its objects to 5 provide an improved method of attaching the web of a reserve roll to the web of an active roll without necessitating stopping of the receiving machine.

Another object is to provide a simple 10 and reliable web changing device which is adapted to attach the web of a reserve roll to the web of an active roll while maintaining said rolls in fixed axial positions.

Another object is to provide a web changing 15 device of the aforesaid character having means associated therewith for automatically severing the web of the active roll upon attachment of the web of the reserve roll thereto.

20 Various other objects and advantages of the invention will hereinafter appear.

The accompanying drawings illustrate 25 an embodiment of the invention which will now be described, it being understood that the embodiment illustrated is susceptible of modification without departing from the spirit and scope of the appended claims.

In the drawings:

30 Figure 1 is a simplified end elevational view of a web supplying mechanism having a web changing device embodying the invention associated therewith;

35 Fig. 2 is an end view of the web changing device shown in Fig. 1, parts thereof being broken away and other parts thereof being shown in section;

40 Fig. 3 is a side elevational view of the web changing device shown in Fig. 1, parts thereof being broken away, and,

45 Figs. 4, 5 and 6 are diagrammatic views illustrating the method of connecting the web of a reserve roll to the web of an active roll by means of the device shown in Fig. 1.

50 Referring to Fig. 1, the same illustrates a web feeding mechanism of the character disclosed in my copending application, Serial No. 683,806, filed December 29, 1923, having a web changing device embodying the invention associated therewith, said device being designated by reference numeral 1. As set forth in said application, the web feeding mechanism includes separate roll supporting frames 2 and 3, rotatably mounted upon shafts 4 and 5, respectively, each of said frames being provided with

spindles adapted to be inserted into opposite ends of a web roll to support the same and to rotate therewith. Each of the roll supporting spindles has a brake drum 6 fixed thereto to be frictionally engaged by a brake shoe 7, and, as shown in Fig. 1, the shoes 7 associated with frame 2 are carried by arms 8 fixed to shaft 4, while the shoes 7 associated with frame 3 are carried by arms 9 fixed to shaft 5. Shafts 4 and 5 are supported at opposite ends by bearing pedestals 10, one of the same being shown in Fig. 1, and said shafts are adapted to be rotated by motors 11 and 12, respectively, through the medium of suitable reduction gearing. As set forth in the aforementioned application, the angular position of each of the frames 2 and 3 can be varied by its associated motor to facilitate installation of the web rolls and to also provide for variation of the tension on the proceeding web.

55 The web changing device 1 is arranged intermediate the roll supporting frames 2 and 3, and is carried by a shaft 13 rotatably supported at opposite ends within suitable bearings in pedestals 10. As best shown in Figs. 2 and 3, the web changing device 1 includes a web pasting member 14 preferably formed of flexible material such as rubber and of such length that the same projects beyond the ends of the rolls carried by frames 2 and 3. Pasting member 14 is clamped between a pair of plates 15 by rivets 16 and said plates have a spacing member 17 therebetween and are secured thereto by rivets 18. Pasting member 14 is carried by tubular members 19 arranged in pairs at opposite ends thereof, the upper ends of said tubular members being secured to plates 15 by rivets 20. Each pair of supporting members 19 is adjustably secured to opposite ends of an arm 21, and each of said arms is fixed to shaft 13 intermediate the ends thereof.

60 For a purpose hereinafter set forth each of the plates 15 has an elongated web holding member 22 associated therewith, said web holding members being pivotally secured to their respective plates by hinges 23 arranged at spaced points throughout the length thereof. Also, as best shown in Fig. 3, each of the web holding members 22 is provided with spaced openings 24 for receiving a felt strip 25, said strip being

woven through said openings in the manner shown. Means is provided for biasing the web holding members 22 into engagement with member 14, said means including 5 a plurality of clips 26 arranged in pairs on opposite sides of said holding members, and a spring 27 associated with each pair of said clips. Each pair of clips 26 is pivotally secured to a pair of supporting 10 posts 28 by pins 29, said posts being fixed within openings in plates 15 and spacing member 17. Springs 27 are arranged within openings in plates 15 and each is held under tension by pins 30 bearing on the 15 outer faces of its associated clips.

As hereinafter set forth, the above described web changing device 1 is rotated during web changing operations, and as shown in Fig. 1 movement thereof is limited 20 by stops 31 and 32 on pedestal 10, said stops being arranged to engage one of the arms 21. Also, as hereinafter set forth, the web changing device 1 is provided with weighted means for moving the same from 25 either extreme position to its other extreme position. Such means includes a weighted arm 33 rotatably mounted on shaft 13 and a cooperating collar 34 fixed to said shaft. As shown in Fig. 3, the lower end of arm 30 33 is bifurcated to receive the collar 34, and said collar is provided with spaced shoulders 35 and 36 to cooperate with opposite sides of arm 33.

The web changing device 1 is also provided with web severing knives 37 and 38, said knives being arranged at substantially right angles to the plates 15 and being secured thereto by rivets 39.

The function and operation of the afore- 40 described web changing device will now be more fully described in connection with Figs. 4 to 6, inclusive. As shown in Fig. 4, the active web roll is mounted on frame 3, and the web thereof is drawn upwardly 45 between a pair of guide rollers 40 and over a compensating roller 41. Prior to exhaustion of the active web roll on frame 3, a reserve web roll is mounted on frame 2. The reserve web roll is arranged so that the 50 same will unwind in a clockwise direction and the outer end thereof is folded backwardly upon itself to provide a flap 42. An adhesive having been applied to the outer face of flap 42 the web is drawn from 55 the reserve roll and passed over the upper edge of pasting member 14, the web changing device being held in the position shown in Fig. 4 by the weighted arm 33. The folded edge of the reserve web roll is then 60 inserted between pasting member 14 and right hand web holding member 22, and the weighted arm is moved from its full line position to its dotted line position. When the active roll mounted on frame 3 65 is about to become exhausted the press is

slowed down to a threading speed and the reserve web roll mounted on frame 2 is rotated by hand in a clockwise direction and at a speed corresponding substantially to such threading speed. Upon rotation of 70 the reserve web roll the web changing device 1 moves in a clockwise direction under the action of the weighted arm 33, and, as shown in Fig. 5, during such movement the outer face of the flap 42 is brought into engagement with the active web and is firmly pressed thereagainst by the flexible pasting member 14. Flap 42 adheres to the proceeding web of the active roll and is drawn between the guide rollers 40, and at the 75 same time the folded edge of the reserve web roll is withdrawn from between pasting member 14 and holding member 22, and knife 38 is brought into engagement with the web of the active roll to sever the same. 80 The web changing device 1 then drops to the position shown in Fig. 6 under the action of the weighted arm 33.

The web changing device operates in a reverse manner from that above described 85 when effecting web changing operations between a reserve roll mounted on frame 3 and an active roll mounted on frame 2. The reserve web roll on frame 3 is arranged 90 so that the same will unwind in a counter 95 clockwise direction and the folded end thereof is passed over the pasting member 14 and is held between the same and the left hand web holding member 22. The weighted arm 33 is then moved into the 100 dotted line position shown in Fig. 6 and the web changing mechanism is then adapted to move in a counter clockwise direction 105 to bring the web from the reserve roll on frame 3 into contact with the web of the active roll on frame 2. Upon attachment of the web of the reserve roll on frame 3 to the active roll on frame 2, knife 37 engages the web of the latter roll to sever the 110 same and the web changing device 1 returns to the position shown in Fig. 4.

What I claim as new and desire to secure by Letters Patent is:

1. In a web renewing mechanism, in combination, a pair of spindles either being 115 adapted to support an active web roll and the other a reserve web roll, the latter having an adhesive applied to a portion on the outer end of its web, and means movable in opposite directions between said rolls to draw 120 the web from said reserve roll and press the adhesive portion thereof against the proceeding web of said active roll while maintaining said rolls in fixed axial positions.

2. In a web renewing mechanism, in combination, a pair of spindles either being adapted to support an active web roll and the other a reserve web roll, the latter having an adhesive applied to a portion on the outer end of its web, and means movable in 125 130

opposite directions between said rolls to draw the web from said reserve roll and to press the adhesive portion thereof against the web of said active roll while maintaining 5 said rolls in fixed axial positions, and means associated with said former means for severing the web of said active roll upon sealing of the end of said reserve roll thereto.

3. In a web renewing mechanism, in combination, a pair of spindles, either being adapted to support an active web roll and the other a reserve web roll, the latter having a folded back portion on the outer end of the web thereof, and having an adhesive 10 applied to one face of such folded back portion, and means for holding the folded portion of said reserve roll, said means being movable in opposite directions between said rolls and being adapted to press the adhesive 15 face of said reserve roll against the web of said active roll.

4. In a web renewing mechanism, in combination, a pair of spindles, either being adapted to support an active web roll and the other a reserve web roll, the latter having a folded back portion on the outer end of the web thereof, and having adhesive applied to one face of such folded back portion, means for holding the outer end of the 20 web of said reserve roll, said means being movable in opposite directions between said rolls and being adapted to press the adhesive face of said reserve roll against the web of said active roll, and means associated with 25 said former means for severing the web of said active roll upon sealing of the web of the reserve roll thereto.

5. In a web renewing mechanism, in combination, a pair of spindles either being adapted to support an active web roll and the other a reserve web roll, the latter having a folded back portion on the outer end of the web thereof and having an adhesive applied to one face of such folded back portion, 30 of a web transferring mechanism movable in opposite directions between said rolls, said mechanism having means associated therewith for detachably holding the folded edge of said reserve roll and for pressing the adhesive face of said reserve roll against the web of said active roll.

6. In a web renewing mechanism, the combination with a pair of spindles, either being

adapted to support an active web roll and the other a reserve web roll, the latter roll 55 having the outer end of its web folded back upon itself and having an adhesive applied to one face of such folded back portion, of a web transferring device movable in opposite directions between said rolls, said device 60 including a yielding member for pressing the adhesive face of the web of the reserve roll against the web of the active roll and means on opposite sides of said member for detachably holding the folded edge on the 65 outer end of the web of the reserve roll during web transferring operations.

7. In a web renewing mechanism, the combination with a pair of spindles, either being adapted to support an active web roll and the other a reserve web roll, the latter roll 70 having the outer end of its web folded back upon itself and having an adhesive applied to one face of such folded back portion, of a pivoted web transferring device located between said spindles and movable in opposite directions through a given range, said device 75 including a yielding member for pressing the adhesive face on the outer end of the web of the reserve roll against the web of the active roll, means on opposite sides of said member for detachably holding the folded edge of the reserve roll during web transferring operations and weighted means associated with said element for biasing the 80 same from either extreme position towards its opposite extreme position.

8. In a web renewing mechanism, in combination, means for supporting an active web roll and a reserve web roll in a parallel 85 relation, the latter having the outer end of its web folded back upon itself and having an adhesive applied to one face of such folded back portion, of a web transferring device movable in opposite directions between said rolls, said device including a yielding member for pressing the adhesive face of the web of said reserve roll against the web of said active roll and having means associated therewith for detachably holding the folded 90 edge of said reserve roll during web transferring operations.

In witness whereof, I have hereunto subscribed my name.

JOHN S. COLDWELL.
